UNITED STATES PATENT OFFICE.

GEORGE H. EVERSON, OF PITTSBURG, PENNSYLVANIA.

MANUFACTURE OF DEEP-FLANGE SECTIONS.

950,280.

Specification of Letters Patent. Patented Feb. 22, 1910.

Application filed November 11, 1908. Serial No. 462,058.

To all whom it may concern:

Be it known that I, GEORGE H. EVERSON, a resident of Pittsburgh, in the county of Allegheny and State of Pennsylvania, have invented certain new and useful Improvements in Manufacture of Deep-Flange Sections, of which the following is a specification.

The primary object of this invention is to produce deep flange sections without impairing the stability of the metal, and particularly without weakening the web, so that such sections may be produced by an operation which is substantially continuous, *i. e.*, continuous with the rolling of the metal from slabs or ingots.

The limitations in producing flanged sections by rolling are well recognized. It is practicable to roll flanges of a depth of from two to three inches without seriously impairing the metal. The peripheries of the rolls travel faster than those portions nearer the roll centers intersected by the grooves. With deep grooves the flanges wedge or bind therein and cannot respond to the more rapid movement of the web transmitted from the roll peripheries. The result is that the metal is injuriously strained, and in some cases the web is ruptured. Sections thus produced are not available for bridge and like structural work where full strength is required of the web. The result is that for such uses the deep-flange sections are built up, the flange and web members being rolled separately and riveted together so that their cost is much greater than a like section formed by rolling.

The present invention is designed to obviate these difficulties and eliminate the expense of fabricating and riveting by providing for the production of sections having integral flanges of any desired width. In the preferred practice a blank is rolled with web and flange members finished as to width but in such angular relation to each other that the blank is produced in a roll pass shallower than the finished section, so shallow that no portion of the metal is subjected to injurious unequal rolling. With the web and flanges fully proportioned the finished section is produced by simply bending the blank to place those parts in their final an-

gular relation. The initial heat for the rolling operation is sufficient for the final bending so that the shapes are produced by a continuous operation, the rolling of the blank being immediately followed by the bending which gives to the section its finished form.

In practicing the method, the blank is preferably rolled with angular longitudinal projections and fillets or grooves at the junc- 55 tures of the web and flange members, thereby not only perfectly forming said members 60 in the rolling operation, but also by the same operation accurately defining and proportioning the metal at the angles or corners, the same being in no way disturbed or im- paired by the subsequent bending. It is 65 further characteristic of the invention that the blanks are rolled with corner-forming projections disposed downwardly so that the direction of the vertical bending pressure is upward rather than downward. The result 70 is that the blanks move from the final roll pass on to a roll table and the mechanism for exerting vertical pressure may be arranged and operated, from beneath, which obvi- 75 ously is much more convenient and affords 80 a more expeditious operation than though it were necessary to so support the blanks as to permit of downward rather than upward bending.

The invention may be practiced in pro- 85 ducing sections of various shapes. In some instances, particularly for a relatively shallow section, the blank may be so rolled that only a single bending operation is necessary to give it final form. With other sections, 90 and particularly where the flanges are relatively deep, two such operations are had.

In the accompanying drawings, Figure 1 is a view of a final roll pass for producing a blank for one form of a deep flange section, 95 the blank being also shown. Figs. 2 and 3 are views of mechanism for bending the blank of Fig. 1 into finished form, said views indicating by full and dotted lines the several steps of the bending operation. Fig. 4 100 is a view similar to Fig. 1 illustrating a blank having relatively narrow flanges adapted to be given final form by a single operation, that operation being indicated by full and dotted lines in Fig. 5. Figs. 6 to 105 11, inclusive, show various sectional shapes

with appropriate mechanisms for bending the blanks into final form. Fig. 12 illustrates the section formed by the bending mechanism of Fig. 11.

5 Referring to Figs. 1, 2 and 3, the relatively shallow roll pass A is shaped to produce a substantially flat blank, of which 1 is the web and 2 the flange members. The rolls are preferably so turned as to produce 10 the right angle longitudinal projections 3 on the under side of the blank at the junctures of the web and flange members, and corresponding fillets or grooves 4 in the upper face of the blank. The metal is curved at 15 where the flat surface of web 1 merges into one of the inclined flat faces 6 of projections 3, and similar curves 7 are provided where flanges 2 merge into the outer leg 6' of projection 3. Obviously, the web and 20 flange members may be any desired width. At the completion of the rolling operation, the blank passes onto a table or horizontal support consisting of a series of rollers 8, as many such rollers being employed as may 25 be desired. These rollers are each grooved at 9 to receive angular projections 3, thereby maintaining the blank in correct position for the bending operation. The right angle projections 3 are of the form, both as to 30 thickness and shape, of the corners of the finished section, and to complete the latter it is only necessary to press the angular projections into the plane of web 1, which operation either partially or wholly completes 35 the forming of the section.

For wide-flange channels of the form shown in Figs. 1 to 3, two bending operations take place. The first is accomplished by means of the notched knuckles 10, pivoted to the upper ends of links 11, which in turn are connected to the toggle levers 13 operated by the piston rod 14 of a suitable ram or power cylinder not shown. For the first bending, the notched knuckles 10 embrace 45 the corners or projections 3, the arrangement being such that the upward bending pressure is applied to the corners and to the inner faces 6 of the projections, and in this first operation the metal is so bent as to 50 eliminate curves 5 and place legs or branches 6 of the angular projections in the plane of web 1. At the completion of this first operation, the parts are in the position shown in dotted lines in Fig. 2, with the outer faces 55 6' of the projections turned straight upward, and with the flanges inclined outwardly due to curves 7. To eliminate these curves and thereby place the whole of the flange at right angles to web 1, the flanges are engaged by 60 the laterally movable pressing heads 15 which when moved inward straighten up the flanges, obliterating curves 7, as in Fig. 3. It will be noted that the first bending operation is accomplished by upward pressure, the

mechanism moving upwardly and flange 65 members 2 away from the roller support. This direction of the pressure is quite important, as thereby the invention may be practiced with a very simple form of roll table, it being only necessary for the rolls to 70 be grooved to accommodate the angular projections of the blank. During this bending operation it is necessary to hold the blank or at least the web portion thereof from moving upward. This may be accomplished 75 by means of two foot-like pressing members 16, suitably supported from above, and preferably positioned to press on the outer portions of the web, or at points adjacent to the angle and groove defined juncture of the 80 web and flanges.

For relatively narrow flanges, the blank may be produced in the roll pass B of Fig. 4, wherein the angular downward projections 3 and opposite fillets or grooves 4 are 85 formed as above described, but in which the relatively narrow flange members 2' are rolled to their finished form with relation to the right angle projections 3, the same being inclined upwardly and outwardly, as shown. 90 In this form, the curves 7 of Fig. 1 are omitted, so that the bending by knuckles 10 places the flanges in their finished position with relation to the web, as illustrated in Fig. 5. With such relatively narrow 95 flanges, the blank-forming rolls may be so turned as to space the flange members 2' in such inclined position as to produce the blank in a comparatively shallow roll pass so that there is no injurious unequal rolling 100 or straining of the metal. It is obvious, however, that the comparatively narrow flanges may also be produced by the bending operations indicated in Figs. 2 and 3.

For producing channel sections of the 105 shape shown in Figs. 6 and 7, wherein the extremities of the flanges are turned inwardly, as indicated at 17, the bending operations are the same as in the operation described of Figs. 1 to 3, the substantially 110 flat blank being rolled with said projections at the extreme edges thereof.

For channel sections like that shown in Fig. 8, wherein the outer portions of the flanges are T-shaped, as indicated at 18, the 115 first bending operation is by means of knuckles 10, as above described. For the second and final bending, triangular heads 19 are substituted for heads 15, the same fitting the outside angle of the T head and thereby 120 securing the hold necessary to move the flange to its final position. It will be understood that the T heads are rolled on the blank, the same as projections 17 of Figs. 6 and 7.

For channels having outwardly disposed extremities 20, as in Figs. 9 and 10, the blank is bent up around a trough-like die 21, suit-

ably supported above the roll table, the die having the laterally projecting wings 22. This is designed for use where the extensions 20 are too wide to be rolled in finished relation with the flanges. Hence the blank is substantially flat, being provided with the downward angular projections 3 for the main or lower corners, and upward projections 23 which define the corners at the inner edges of extensions 20. The first bending operation is accomplished by knuckles 10, as above described, and the second and final bending with heads 19, like those shown in Fig. 8.

15 In producing the M or W section of Fig. 12, a die 24 of M-form is suitably supported above the roll table. The blank is rolled with a central downward angular extension 25 and two similar corner defining upward extensions 26. The bending elements consist of two vertically movable angular heads 27 which when raised carry the blank upwardly into the cavities of the die, placing the corners of the blank in or around the corners of the die and giving perfect form to the finished section.

The foregoing are only some of the numerous sectional shapes produced by practicing the invention. In each, it will be seen that 30 relatively wide flanges are produced by an operation which is substantially a continuation of the rolling, the bending mechanism being simply an extension of the rolling mechanism and so arranged as to receive the 35 blanks directly from rolls so that the metal is bent into shape while still hot.

I claim:—

1. The method of producing a section with a web and deep flanges, consisting in rolling 40 the web and flanges each into its final form— save distortions adjacent the junctures thereof—and in such relation that the roll pass is shallower than the finished section, and then eliminating the distortions and placing 45 the web and flanges in finished angular relation and each in finished form.

2. The method of producing a section with a web and deep flanges, consisting in rolling a blank with deep flange members 50 so disposed to the web due to curved portions adjacent their juncture that the blank is produced by a relatively shallow roll pass wherein the metal of the web is not injured by strains resulting from varying speeds of a 55 deep roll pass, and then placing the web and flanges in finished relation by straightening said curved portions.

3. The method of producing sections with deep flanges, consisting in rolling a blank 60 with web and flange members with opposite angles and fillets at the junctures of the web and flanges, the web and flanges being in such relation due to distortions adjacent their juncture that the blank is produced in

a roll pass shallower than the finished section, and then bending the blank to eliminate the distortions and thereby place the web and flanges in finished angular relation. 65

4. The method of producing sections with wide flanges, consisting in rolling a blank 70 with web and flange members with permanent angles and corresponding fillet depressions at the junctures of the web and flanges, the web and flanges being in such relation due to distorted portions adjacent the juncture of the web and flanges that they are produced in a roll pass shallower than the finished section, and then applying bending pressure so that the web and flanges will 75 assume proper position. 80

5. The method of producing sections with deep flanges, consisting in rolling a blank with web and flange members with right angle projections at the junctures of the web and flanges, the web and flanges being in 85 such relation due to distortions adjacent their junctures that the blank is produced in a roll pass shallower than the finished section, and then removing the distortions by bending the blank until the corner of the 90 angle is brought to the plane of the web member.

6. The method of producing deep flange sections, consisting in rolling a blank with web and flange members with angular projections at one face of the blank, the web member merging into the inner branches of the projections and the flange members extending from the outer branches thereof, the web and flange members being in such 95 relation due to distortion near the angular projection that the blank is produced in a roll pass shallower than the finished section, and then placing the web and each of the flange members in final relation by bending 105 the distorted portion with the angular projections forming the corners of the finished section.

7. The method of producing deep flange sections, consisting in rolling a blank with 110 web and flange members having straight faces with right angle projections at one face of the blank connecting the web and flanges, the metal being curved to join the straight faces of the web and the projections, 115 the web and flange members being in such relation that the blank is produced in a roll pass shallower than the finished section, and then straightening out the curves connecting the web member and the right angle projections for increasing the angular relation 120 between the web and flange members and to provide the finished section with right angle corners.

8. The method of producing deep flange 125 sections, consisting in rolling a blank with web and flange members and with angular projections at one face of the blank, the

blank being curved at the junctures of the web and flange members with the angular projections, the web and flange members being in such relation that the blank is produced in a roll pass shallower than the finished section, and subsequently straightening the curves connecting the web member and said projections and the curves

connecting the flange members and the angular projections.

In testimony whereof I affix my signature in presence of two witnesses.

GEORGE H. EVERSON.
